[57] CLAIM

The ornamental design for a server, as shown and de-
scribed.

DESCRIPTION

FIG. 1 is a front elevational view of a server showing
my new design, the right foldable leaf in fully extended
position and the left foldable leaf in partial extended
position;FIG. 2 is a right side elevational view thereof with the
foldable leaf in closed position, the left side being a
mirror image thereof;

FIG. 3 is a top plan view thereof; and

FIG. 4 is a sectional view taken along line 4—4 of FIG.
1.The rear elevational view of the server is convention-
ally flat and unornamented.
